UNITED STATES PATENT OFFICE.

JOSEPH ANTONUCCIO, OF OAKLAND, CALIFORNIA.

GAS-BURNER.

1,082,725.

Specification of Letters Patent.

Patented Dec. 30, 1913.

Application filed July 15, 1912. Serial No. 709,594.

To all whom it may concern:

Be it known that I, JOSEPH ANTONUCCIO, a citizen of the United States, residing at Oakland, in the county of Alameda and 5 State of California, have invented a new and useful Gas-Burner, of which the following is a specification in such full and clear terms as will enable those skilled in the art to construct and use the same.

10 This invention relates to a combination gas cock and gas burner used for heating purposes and an object of the invention is to produce an efficient mixing device whereby the air and gas will be properly mixed 15 at all times, even though the supply of gas may be very much reduced.

It will be understood by those skilled in the art that where a needle valve is used to reduce the quantity of gas passing to the 20 mixing chamber that the velocity of flow of the gas is so greatly retarded and interfered with that the mixing is very inefficiently done. Therefore, with this invention means are provided whereby the nozzle 25 which delivers the gas to the mixing chamber has a chamber of considerable size immediately adjacent it, the regulation being accomplished by the valve which does not interfere with the opening from the nozzle 30 into the mixing chamber.

Another object of the invention is to provide means whereby the pilot light will have gas supplied to it prior to the supply of gas to the burner proper.

35 In the drawings in which the same numeral of reference is applied to the same portion throughout the several views, Figure 1 is a vertical sectional view through the burner, mixing chamber and pilot light, Fig. 2 is a plan view of the burner, mixing chamber and pilot light, Fig. 3 is a view in end elevation of the pilot light, gas valve and burner, Fig. 4 is a vertical sectional view of a modified form of the gas supply 40 valve, the plane of section being chosen to illustrate the relative position of the two ports in said valve, Fig. 5 is a vertical sectional view of the gas valve transverse to the valve plug, one of the ports therein being shown in full lines and the other in dotted lines, and Fig. 6 is a front view of said valve.

The numeral 1 represents the gas supply pipe to which the gas regulating valve 2 is 55 secured in the usual manner. The gas regulating valve has a small nozzle 3 and has

external and internal threads at 4. Revolvable within the valve is a frustoconical plug 5 having the handle 6 to rotate the same. A screw 7 holds this plug in its proper place 60 in the valve and the plug 5 is provided with a stop 8 to prevent it from being turned more than a given amount, the fixed part of the valve having a stop 9 which the stop 8 strikes. This plug supplies the pilot light 65 with gas and its handle is so placed as to be operated with the left hand. Between the plug 5 and the screw threaded portion of the valve there is a plug 11 slightly larger than the plug 5 which supplies gas to the 70 nozzle 16. This plug has a screw 11' to hold it in place and its handle 11'' is placed at the right.

The object of placing the valve plug handles in the manner shown is to take advantage of an almost universal habit of people. All right handed persons when undertaking to light a burner of this character will strike the match in the right hand and will reach out with the left hand to turn the 75 gas on in the burner. This naturally brings the left hand to the pilot light handle. The next operation of the person is to throw the match away whereupon the right hand will be used, and in this instance the burner 80 valve will be within convenient reach at once. It thus becomes almost a certainty that the proper valve will be opened first.

Supported by the valve casing is a mixing chamber 12, said mixing chamber having a conical portion 13 and having arms 13', which have an opening therein to receive the end of the valve casing. The mixing chamber is curved upwardly as shown at 14 and has a pan like top 18.

90 Resting upon the top 18 is a shallower pan shaped member 19 having a flange extending over the edge of the member 18, lugs 20 spacing said member a short distance away from the member 18 and a short 95 distance above the same.

The pilot light is supported on the nozzle 3 as indicated at 21 and it has a long nozzle 22 extending into proximity to the edge of the burner top 18. Screwed within the 100 valve is a gas nozzle 16, said gas nozzle having an opening 17, which is of sufficient size to supply the given burner with the necessary amount of gas.

105 It will be observed that between the valve supplying the burner with gas and the end of the nozzle where the opening 17 is placed,

there is a considerable chamber which is for the purpose of always retaining a supply of gas so that the gas flowing from the nozzle tip will always move therefrom at a good velocity to be adequately mixed with the air in the mixing chamber whether at a high or low pressure; an effect that is difficult to accomplish when the needle valve at the opening 17 is used.

10 In Figs. 4, 5 and 6 a valve is shown which accomplishes the objects of the two valves shown in the preceding figures. In these figures the valve casing is indicated at 25, a threaded portion of the valve at 26 and the 15 nozzle leading to the pilot light at 27. This valve is also threaded at 28 to receive a pipe 29.

The valve proper comprises a frustoconical plug 30 held in place by means of a 20 screw 31 and operated by means of a handle 32 at the left of the valve, the same as is used for the pilot light in the preceding figures. This valve plug has two ports therein, one 25 at 33 and one at 34, said ports being so spaced apart and shaped as to supply the pilot light with gas prior to the time the burner is supplied with gas, note Fig. 5, in which gas is flowing fully to the pilot light.

Further movement of the valve supplies the burner with gas, and when the burner 30 is receiving a further supply of gas a further movement of the valve will cut off the pilot light from the supply of gas altogether.

Having thus described my invention what 35 I claim as new and desire to secure by Letters Patent of the United States is as follows:

In a gas burner, the combination of a shallow pan, a mixing chamber leading 40 from the lower side of said pan, a smaller flanged pan loosely fitting into the first pan to cause the mixed gas to be discharged therefrom in an annulus, a gas supply pipe, a cut off valve connected with the pipe and 45 mixing chamber, and a removable gas tip within the mixing chamber, substantially as described.

In testimony whereof I have hereunto set 50 my hand this 3 day of May A. D. 1912, in the presence of the two subscribed witnesses.

JOSEPH ANTONUCCIO.
